[57] **CLAIM**

The ornamental design for a bracelet, as shown and described.

DESCRIPTION

FIG. 1 is a front or rear elevational view of a bracelet showing my new design;

FIG. 2 is a side elevational view thereof;

FIG. 3 is a top plan view thereof;

FIG. 4 is a cross-sectional view taken along the line 4—4 of FIG. 3, a portion thereof being removed for ease of illustration; and,

FIG. 5 is a bottom plan view thereof.
